UNITED STATES PATENT OFFICE.

JOHN HAYWARD PARSONS, OF FERNDALE, MICHIGAN.

GASOLINE-RESERVE-SUPPLY APPARATUS.

Application filed October 24, 1921. Serial No. 510,137.

To all whom it may concern:

Be it known that I, JOHN H. PARSONS, a citizen of the United States, and residing at Ferndale, county of Oakland, and State of Michigan, have invented a new and Improved Gasoline-Reserve-Supply Apparatus, of which the following is a specification.

This invention relates to gasoline reserve supply apparatus for automobiles, motor boats, and the like and has for its primary object the reservation within the usual gasoline supply tank of all the gasoline below a predetermined level as a reserve supply, with provisions whereby an alarm will be given when such level of the gasoline in the tank is reached, after which the reserve supply can be utilized in driving the automobile to a filling station.

Another object of this invention is to arrange the suction pipe leading from the gasoline tank to the carburetor so that gasoline is at all times drawn off from the bottom of the tank, thereby preventing the accumulation of water or fuel of low gravity at the bottom of the tank to render the reserve supply of inferior quality to the main supply of gasoline.

A further object of my invention is the provision of simple and comparatively inexpensive means for preventing the consumption of the full supply of fuel by the engine without first requiring the driver to operate the mechanism to permit the use of the reserve supply and thereby calling his attention to the fact that it is necessary to obtain a fresh supply of gasoline, such means being adaptable for ready insertion into the threaded socket ordinarily used for connecting the gasoline tank with the vacuum feed tank adjacent the carburetor or with the carburetor direct when a pressure system is employed.

The above and other objects of my invention will be apparent from the following description wherein reference is made to the accompanying drawings illustrating preferred embodiments of my invention, and wherein similar reference numerals designate similar parts throughout the several views.

In the drawings:—

Fig. 1 is a central sectional view through my improved gasoline reserve supply apparatus in position upon the gasoline supply tank;

Fig. 2 is a transverse sectional view taken

substantially on the line 2—2 of Fig. 1, the ports for permitting the breaking of the vacuum, as hereinafter explained, being shown in open position;

Fig. 3 is a similar view with the ports closed to prevent breaking of the vacuum by air within the tank;

Fig. 4 is a central sectional view similar to Fig. 1, of a slightly modified form of my reserve supply apparatus;

Fig. 5 is a transverse sectional view on the line 5—5 of Fig. 4;

Fig. 6 is a diagrammatical view, with parts in section showing a form of my reserve supply apparatus arranged so that the reserve supply can be brought into use by turning a valve mounted on the dash-board of an automobile;

Fig. 7 is a side elevation of such valve with the dash-board shown in section, and

Fig. 8 is a detail front view of the dash-board and valve.

Referring now to the drawings the numeral 5 designates a gasoline supply tank of the ordinary or any desired construction having an internally threaded socket 6 welded or otherwise secured to the upper surface thereof for the reception of the threaded lower extremity of the valve casting 7 arranged also to form a connection for the rear extremity of the pipe line 8 leading to the usual vacuum tank or to the carburetor. As herein shown the extremity of the pipe line is flared, as at 9, to fit over the tapered extremity of the threaded portion 7^a of the valve casing, and being pressed tightly against same by the flared wall of the nipple 10. This is the standard S. A. E. form of solderless union for rendering carburetor tubing connections air tight, but it is to be understood that any desired form of connection may be employed that will serve the same purpose.

Extending vertically through the valve casting 7 and downwardly to a position adjacent the lower wall of the tank 5 is the feed pipe 11, which, in the embodiment illustrated in Figs. 1, 2 and 3, is divided substantially centrally by a longitudinal wall 105

12. A port 13 is arranged to register with the opening in the portion 7^a of the valve casting leading to the pipe line 8, and thereby connects one compartment of the feed pipe 11 with the pipe line. A port 14 is arranged 110 in the wall of the opposite compartment of the feed pipe at a short distance from the

lower extremity thereof, this port being spaced a predetermined distance above the bottom and being normally submerged in the liquid fuel until the level of such fuel falls to the height of such port. Upper ports 15 and 16 are arranged in the opposite compartments of the feed pipe adjacent their uppermost extremities and apertures 15^a and 16^a in the valve casing respectively connect these upper ports with a channel 17 formed in the internal wall of the rotatable valve member 18 and partially encircling the same, as can be best seen in Figs. 1 and 2. The valve member 18 is provided with a lever 15 or thumb piece 19 to enable its rotation to a position closing one of the upper ports 15 or 16, substantially as shown in Fig. 3.

With the construction illustrated in Figs. 1 to 3 the liquid gasoline is drawn off from the bottom of the tank 5 through the compartment of the feed pipe 11 connected with the pipe line 8, through which suction may be applied to lift the fuel in the usual manner of vacuum feed systems, or the liquid can be forced therethrough by pressure in the usual manner of pressure feed systems. In either case the liquid is fed through one compartment of the feed pipe 11 to the pipe line 8 and thence to the carburetor of the engine with or without the intervention of a vacuum tank. This feeding of the liquid is continued in this manner as long as the level of the liquid remains above that of the port 14 in the opposite compartment of the feed pipe 11. When the liquid level falls sufficiently to permit the entrance of air into the port 14, the air will be drawn through the right hand compartment of the feed pipe in Fig. 1 to the port 16, thence around the channel 17 to the port 15 in the left hand compartment whence it enters the pipe line 8 and breaks the vacuum or pressure therein by providing a path whereby air can be drawn into the pipe line more easily than can liquid gasoline. When this occurs the feeding of fuel from the tank 5 to the carburetor ceases until the valve member 18 is rotated to close one of the ports 15 or 16 to stop the passage of air to the pipe line 8. Thereupon the liquid gasoline remaining in the tank below the port 14 will be drawn into the pipe line 8 through the same compartment of the feed pipe 11 that was utilized when drawing upon the fuel of the main gasoline supply.

The valve member 18 is suitably seated, as upon the tapered upper extremity 20 of the casing 7 and preferably held in seated position by a coil spring 21 arranged between the valve member and a washer 22 suitably held upon the casing 7, as by a split ring 23 fitting in an annular groove in the casing.

In the embodiment illustrated in Fig. 4 the valve casing 22 is arranged as a straight member with its lower extremity threaded into the nipple 6^a of the tank 5^a and receiv-

ing on its threaded upper extremity the nipple 10^a holding the rear extremity of the pipe line 8^a in air tight engagement with the valve casing. The feed pipe 11^a is preferably formed substantially of the shape shown in Fig. 5 and has its upper extremity mounted in the valve casing in alignment with the pipe line 8^a so that suction will draw gasoline from the bottom of the tank 5^a through the entire length of the feed pipe. The port 24 in the feed pipe 11^a opens into the passage 25 in the valve casing, which in turn opens into the channel 17^a of the rotatable valve member 18^a. The port 26 diametrically opposite the passage 25 in the wall of the valve casing connects the channel 17^a with the passageway 27 preferably formed by pressing inwardly one side of the tube forming the feed pipe 11^a (see Fig. 5), the space between such indent portion 11^b of the feed pipe and the inner wall of the valve casing permitting the passage of air to break the vacuum when the level of the liquid in the tank 5^a falls sufficiently. A sleeve 28 of sufficient length to reach to a predetermined level adjacent the bottom of the tank 5^a is arranged to encircle the feed pipe 11^a, and is preferably secured in the lower portion of the socket 6^a so as to form a continuation of the inner wall of the valve casing.

The operation of the embodiment illustrated in Figs. 4 and 5 is as follows:—The liquid gasoline is drawn from the bottom of the tank 5^a through the feed pipe 11^a and pipe line 8^a to the vacuum tank or carburetor of the engine as long as the level of the liquid in the tank 5^a remains above the lower extremity of the sleeve 28. When, however, the liquid falls below the sleeve 28, air is drawn into the passageway between the inner wall of the sleeve 28 and the indent portion 11^b and passes through the port 26, channel 17^a, passage 25 and port 24 into the feed pipe 11^a, thereby breaking the vacuum. The liquid flow is thus cut off and the driver is warned by the action of his carburetor within a short time thereafter that his gasoline supply is becoming low. Or if he fails to note the carburetor's action he will be forced to come to a stop after driving a short distance because of the consumption of all of the gasoline in the vacuum tank. He must then turn the valve member 18^a to a position closing one of the ports 24 or 26, whereupon the air passage is closed and suction in the pipe line 8^a will serve to draw liquid gasoline from the reserve supply at the bottom of the tank 5^a below the sleeve 28. To limit the rotation of the valve member 18^a I preferably provide a lug 37 arranged to contact the stop pin 38 at the extremes of its movement.

The embodiment illustrated in Figs. 6, 7 and 8 utilizes a feed pipe 11^c divided longi-

tudinally into compartments, through one of which, as for example that shown at the right hand side in Fig. 6, liquid gasoline is drawn into the pipe line 8^a secured at its rear extremity upon a T shaped valve casing 7^a and leading to a valve casing 29 mounted upon the dash-board 30 of an automobile and thence to the vacuum tank or carburetor in the usual manner. The valve casing 29 is herein illustrated as substantially T shaped with three passageways radiating from the central portion. The pipe line 8^a is preferably connected with the central of these passageways 32 at the right side of the casing 29 as herein illustrated. A port 14^a is positioned in the opposite compartment of the feed pipe 11^a at any desired height above the bottom of the tank 5^a and an upper port 15^a connects this compartment with the bypass pipe 33 connecting the left hand portions of the T shaped valve casings 7^a and 29. The valve 34 is suitably seated in the casing 29 and provided with three radial passages adapted to connect the passageways 31, 32 and 33 when in the position shown in Fig. 6. This position is the one maintained when the main supply of gasoline is being drawn from the tank 5^a. In operation the liquid gasoline is drawn upwardly from adjacent the bottom of the tank 5^a through the right hand compartment of the feed pipe 11^a into the pipe line 8^a, passageways 31 and 32 of the valve casing 29, into the continuation 8^a of the pipe line leading to the vacuum tank or carburetor. This action continues until the liquid level falls below the port 14^a in the opposite compartment of the feed pipe 11^a, whereupon air is drawn through such compartment into the bypass pipe 33 and the passageway 32 of the valve casing 29, breaking the vacuum and thereby stopping the flow of the liquid gasoline. The engine will thereupon give warning, as hereinbefore described, that the fuel supply is low. The valve 34 can then be rotated by grasping the knob 35 thereof and turning it through a quarter revolution, thereby moving the radial passage of the valve 34 opening into the bypass 33, as shown in Fig. 6, into position to open into the central passageway 31 of the valve casing 29, and simultaneously swinging the passage formerly opening into the central passage 31 into position to register with the right hand passageway 32. The left hand passageway 33 is closed by this movement of the valve 34, thereby preventing the entrance of air to the pipe line 8^a to further prevent the formation of a vacuum to draw up liquid fuel. In Fig. 8 I have illustrated a dial adapted to be mounted on the dash-board 30 with a pointer 36 mounted on the stem of the valve 34 to show whether the main or reserve supply of gasoline is being drawn upon. While it will be apparent that the illus-

trated embodiments of my invention herein disclosed are well calculated to adequately fulfill the objects and advantages primarily stated, it is to be understood that the invention is susceptible to variation, modification and change within the spirit and scope of the subjoined claims.

Having described my invention I claim:—

1. In a device of the character described, a tank adapted to contain fuel, a feed pipe mounted therein with its lower extremity adjacent the bottom of the tank and its upper extremity projecting above the tank, the upper portion of the feed pipe having a port therein exterior of the tank, the upper portion of the feed pipe having a second port therein opening into a pipe line through which fuel is adapted to be conveyed to the engine, means for admitting air from within the tank to said first-mentioned port to break the flow of fuel through the pipe line when the fuel level falls to a predetermined plane, and means for rendering said last named means inoperative at will to resume feeding of fuel through the pipe line. 90

2. In a device of the character described, a tank adapted to contain fuel, a feed pipe mounted therein with its lower extremity adjacent the bottom of the tank and its upper extremity projecting above the tank, the upper portion of the feed pipe having a port therein exterior of the tank, the upper portion of the feed pipe having a second port therein opening into a pipe line through which fuel is adapted to be conveyed to the engine, means for admitting air from within the tank to said first-mentioned port to break the flow of fuel through the pipe line when the fuel level falls to a predetermined plane, and means for closing said first-mentioned port at will to resume feeding of fuel through the pipe line. 105

3. In a device of the character described, a tank adapted to contain fuel, a feed pipe mounted therein with its lower extremity adjacent the bottom of the tank and its upper extremity projecting above the tank, the upper portion of the feed pipe having a port therein exterior of the tank, the upper portion of the feed pipe having a second port therein opening into a pipe line through which fuel is adapted to be conveyed to the engine, means for admitting air from within the tank to said first-mentioned port to break the flow of fuel through the pipe line when the fuel level falls to a predetermined plane, a valve encircling the upper portion of the feed pipe and rotatable to close said first-mentioned port to permit resumption of the flow of fuel through the pipe line. 120

4. In a device of the character described, a tank adapted to contain fuel, a feed pipe mounted therein with its lower extremity adjacent the bottom of the tank and its up- 130

per extremity projecting above the tank, the upper portion of the feed pipe having a port therein exterior of the tank, the upper portion of the feed pipe having a second port therein opening into a pipe line through which fuel is adapted to be conveyed to the engine, a passageway exterior of the feed pipe for admitting air from within the tank to said first-mentioned port to break the flow of fuel through the pipe line, and a valve rotatable about the upper portion of the feed pipe and adapted to close said passageway to permit resumption of the flow of fuel.

5. In a device of the character described, a tank adapted to contain fuel, a feed pipe mounted therein with its lower extremity adjacent the bottom of the tank and its upper extremity projecting above the tank, the upper portion of the feed pipe having a port therein exterior of the tank, a pipe line connected with the upper portion of the feed pipe through which fuel is adapted to be conveyed to the engine, a tube extending from within the tank to a position above the tank adjacent said port in the feed pipe, said tube having a port exterior of the tank, a valve rotatable about the feed pipe and said tube and having a channel in its inner wall adapted when in one position to connect the ports in said tube and feed pipe, and means for rotating said valve to close one of said ports.

6. In a device of the character described, a tank adapted to contain fuel, a feed pipe mounted therein with its lower extremity adjacent the bottom of the tank and its upper extremity projecting above the tank, the upper portion of the feed pipe having a port therein exterior of the tank, a pipe line connected with the upper portion of the feed pipe through which fuel is adapted to be conveyed to the engine, a tube extending from within the tank to a position above the tank adjacent said port in the feed pipe, said tube having a port exterior of the tank, a valve rotatable about the feed pipe and said tube and having a channel in its inner wall adapted when in one position to connect the ports in said tube and feed pipe, means for rotating said valve to close one of said ports, and means for maintaining the valve in either of said positions.

7. In a device of the character described, a tank adapted to contain fuel, a feed pipe mounted therein with its lower extremity adjacent the bottom of the tank and its upper extremity projecting above the tank, the upper portion of the feed pipe having a

port therein exterior of the tank, a pipe line connected with the upper portion of the feed pipe through which fuel is adapted to be conveyed to the engine, a tube extending from within the tank to a position above the tank adjacent said port in the feed pipe, said tube having a port exterior of the tank, a valve rotatable about the feed pipe and said tube and having a channel in its inner wall adapted when in one position to connect the ports in said tube and feed pipe, means for rotating said valve to close one of said ports, and a spring engaging the valve to maintain it in either of said positions.

8. In a device of the character described, a tank having a threaded socket mounted therein, a valve casing threaded into said socket, a feed pipe mounted in the casing and extending from above the tank to adjacent the bottom thereof, said feed pipe being divided longitudinally into compartments, a pipe line adapted to receive fuel from one of said compartments, such compartment also having a port therein above the connection with the pipe line, the other compartment of the feed pipe having an upper port adjacent the port in the first mentioned compartment and a lower port spaced a predetermined distance from the bottom of the tank, a valve having a channel connecting the upper ports of both compartments, and means for moving said valve to a position closing one of said ports.

9. In a device of the character described, a tank having a threaded socket mounted therein, a valve casing threaded into said socket, a feed pipe mounted in the casing and extending from above the tank to adjacent the bottom thereof, said feed pipe being divided longitudinally into compartments, a pipe line adapted to receive fuel from one of said compartments, such compartment also having a port therein above the connection with the pipe line, the other compartment of the feed pipe having an upper port adjacent the port in the first mentioned compartment and a lower port spaced a predetermined distance from the bottom of the tank, a valve seated upon the valve casing and having a curved channel in its inner wall adapted when in one position to connect the upper ports of both compartments, said valve being rotatable at will to a position closing one of said ports.
